ELECTRON DISCHARGE DEVICE

George C. Sziklai, Princeton, N. J., assignor to
 Radio Corporation of America, a corporation of
 Delaware

Application September 6, 1945, Serial No. 614,692

7 Claims. (Cl. 315—6)

1

My invention relates to electron discharge devices useful at ultra high frequencies and more particularly to such devices employing velocity modulation and inductive output and utilizing cavity resonators.

The principal object of my invention is to provide a velocity modulated oscillator capable of delivering high power at high frequencies and with improved efficiencies, and to the methods for modulating said devices.

The novel features which I believe to be characteristic of my invention are set forth with particularity in the appended claims, but the invention itself will best be understood by reference to the following description taken in connection with the accompanying drawing in which Figure 1 is a schematic longitudinal section of an electron discharge device made according to my invention and Figure 2 is a diagrammatic longitudinal section of a modification of the device shown in Figure 1.

In accordance with my invention the electron discharge device is provided with an elongated envelope 10 having a transverse offset portion 10'. Mounted at one end of the envelope is an indirectly heated cathode 11 and beam forming electrode 12, electrons being directed toward a collector 13 at the other end of the envelope. Positioned intermediate the cathode and collector is an electromagnet 15 for providing a magnetic field transverse to the path of the beam of electrons. As a result of this field, the electrons take the curved path indicated and are directed toward reflecting electrode 14 passing through the resonator 16 and being reflected back along the dotted path to the magnetic field which causes the electron path to reverse itself and be directed toward the collector 13. The beam on passing through the grids 16' of the resonator 16 is subjected to a velocity modulation, becomes bunched and, passing through the resonator again, maintains the resonator in oscillation, causing this portion of the device to act in the manner of a reflex oscillator or as a space charge grid Barkhausen oscillator.

The bunched electrons then pass through the grid 17' of the resonator 17 inducing a high frequency voltage in this resonator, which in turn velocity modulates the beam again, thus accentuating the bunching. The beam then is directed through the grids 18' of the resonator 18, energy being extracted in a manner now well known. The electrons are then collected by the collector 13. A coupling loop 30 may be used for extracting energy in the usual manner.

2

The voltage sources 19, 20 and 21 are provided for applying the proper voltages to the various electrodes, the resonators 16, 17 and 18 being maintained at high positive potentials, the reflector 14 being properly biased to reflect the electrons as described above, the collector 13 being maintained at a lower positive potential for receiving the electrons.

Since the same beam current is used in all stages, higher efficiency may be obtained than in conventional oscillators utilizing cavity resonators. The cascade amplifier portion, particularly the resonator 17, acts as a buffer and prevents interaction between the output resonator section 18 and the oscillator section 16. By use of the magnetic field the combination of the oscillator and amplifier sections is made possible with the result that the input power may be materially reduced. It is also obvious that by changing the potential of the reflector 14 within limits the oscillator may be frequently modulated. Thus the output of the device may be frequently modulated by the same means.

In order to amplitude modulate the device the beam current passing the last resonator 18 must be varied. This variation, however, must be effected after the beam passes through the oscillator, otherwise frequency modulation will occur simultaneously. A device for accomplishing amplitude modulation is disclosed in Figure 2.

In Figure 2 like numerals refer to like parts as in Figure 1, the amplifier section alone being different. The beam after being velocity modulated by the oscillator portion of the envelope 25 passes through the buffer stage 17 and enters the deflection field between deflecting plates 22 and 23, deflecting the beam across the aperture or gate 24 in the apertured plate 24, the amount of deflection determining the beam density and hence the output current. The amount of current passing through the gate or aperture is determined by the amplitude of the potential applied to the deflecting plates 22, 23. In order to straighten the beam after passage through the aperture 24, a second set of deflecting electrodes 25 and 26 are provided, these deflecting electrodes being cross-connected with the plates 22 and 23 so that the same potential is applied twice but in opposite directions to straighten out the beam path. The device shown in Figure 2 possesses all of the advantages of the device shown in Figure 1.

While I have indicated the preferred embodiments of my invention of which I am now aware and have also indicated only one specific application for which my invention may be employed,

it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. An electron discharge device having cathode means for directing a stream of electrons along a beam path, an electrode in said path toward which said electrons are directed, means for deflecting said stream at an angle to said path, means for velocity modulating said deflected electrons and returning said electrons along said first path toward said electrode, means for further velocity modulating said returned electrons, and means for extracting energy from said velocity modulated electron stream.

2. An electron discharge device having a cathode for directing electrons along a predetermined path, means for generating a magnetic field transversely to said path for causing said electrons to be deflected from said path, means for velocity modulating said deflected electrons and for directing said electrons back toward said path including a first resonator and a reflecting electrode, a second resonator in the path of said electrons for further velocity modulating said electrons, a third resonator for extracting energy from said electrons, and a collector for said electrons.

3. An electron discharge device having a cathode for directing electrons along a predetermined path, an electrode toward which said electrons are directed, means for generating a magnetic field transversely to said path for causing said electrons to be deflected from said path, means for velocity modulating said deflected electrons and for directing said electrons back toward said path including a first resonator and a reflecting electrode, a second resonator in the path of said electrons for further velocity modulating said electrons, and a third resonator following said second resonator for extracting energy from said electrons.

4. An electron discharge device having an elongated envelope and an offset portion transverse to said elongated portion, a cathode at one end of said electrode and a first electrode at the other end of said envelope, said cathode directing electrons toward said electrode, means positioned adjacent said envelope for directing a magnetic field transversely to said electron path at the transverse portion of said envelope, a reflecting electrode at the end of said offset portion toward which said electrons are directed, a first resonator positioned between said reflecting electrode and the means providing said electromagnetic field, and other resonator means positioned between said first electrode and the transverse portion of said envelope, and including a

second resonator for velocity modulating said electron stream and a third resonator for inductively extracting energy from said velocity modulated electrons.

5. An electron discharge device having cathode means for directing a stream of electrons along a beam path, a first electrode in said path toward which said electrons are directed, means for deflecting said stream at an angle to said path, means for velocity modulating said deflected electrons and returning said electrons along said first path toward said first electrode, and means for further velocity modulating said returned electrons and further means for extracting energy from said velocity modulated electron stream, and means for amplitude modulating said electron stream and including a pair of deflecting electrodes positioned between said last two means.

6. An electron discharge device having cathode means for directing a stream of electrons along a beam path, a first means in said path toward which said electrons are directed, means for deflecting said stream at an angle to said path, means for velocity modulating said electrons and returning said electrons along said first path toward said first means, resonator means for further velocity modulating said electrons and other resonator means for extracting energy from said velocity modulated electron stream, and means for amplitude modulating said electron stream and including a pair of deflecting electrodes positioned between said last two resonators.

7. An electron discharge device having cathode means for directing a stream of electrons along a beam path, a first means in said path toward which said electrons are directed, means for deflecting said stream at an angle to said path, means for velocity modulating said electrons and returning said electrons along said first path toward said first means, resonator means for further velocity modulating said electrons and other resonator means for extracting energy from said velocity modulated electron stream, and means for amplitude modulating said electron stream and including a pair of successively positioned deflecting electrodes positioned along the path of said electrons between said resonators, and an apertured electrode positioned between said pair of deflecting electrodes.
